UNITED STATES PATENT OFFICE.

ROBERT MILLER, JR., OF SCHENECTADY, NEW YORK, ASSIGNOR TO GENERAL ELECTRIC COMPANY, A CORPORATION OF NEW YORK.

RESISTANCE.

1,021,256.

Specification of Letters Patent. Patented Mar. 26, 1912.

Application filed January 7, 1910. Serial No. 536,790.

To all whom it may concern:

Be it known that I, ROBERT MILLER, Jr., a citizen of the United States, residing at Schenectady, county of Schenectady, State 5 of New York, have invented certain new and useful Improvements in Resistances, of which the following is a specification.

My invention relates to resistances for electric circuits, particularly resistances used 10 as shunts in connection with various electrical devices, such as measuring instruments, and the object of my invention is to provide a simple and rugged resistance device or shunt of high efficiency, which has a 15 lower operating temperature than shunts heretofore used and which may be easily and quickly calibrated and adjusted to vary the ohmic resistance of the device.

In accordance with my invention, the resistance or shunt is formed of metal wires 20 or strips of any desired shape interlaced or otherwise suitably arranged to form a network or gauze having numerous meshes through which air or other cooling fluid may 25 circulate freely and thereby maintain the temperature of the resistance within the desired limits. The wires or strips which constitute the network may be arranged in any desired manner so long as they are in contact or in good thermal relation and form 30 an open mesh structure suitably positioned so that air or other cooling fluid may flow freely over and through it. The ohmic resistance of the resistance device or shunt 35 may be varied and the shunt calibrated by varying the conducting capacity of any of the wires, or by shifting the cross wires with reference to the longitudinal wires. In the preferred construction high resistance wires 40 are strung parallel to each other in the same plane while transverse wires are strung on a movable support so as to be in good thermal and electrical engagement with the high resistance wires, so that adjusting the movable support moves all the transverse wires 45 simultaneously to vary the angle between them and the high resistance wires, thereby varying the ohmic resistance of the device.

My invention will best be understood 50 in connection with the accompanying drawing which shows merely for purposes of illustration one of the forms in which my invention may be embodied and in which—

Figure 1 is a plan view of an adjustable

resistance or shunt and Fig. 2 an end view 55 of the adjustable resistance shown in Fig. 1, with a portion broken away to show the relation of the transverse wires to the longitudinal high resistance wires.

I have shown one form of adjustable device embodying my invention comprising a suitable base 1 carrying metallic terminals 2 between which a series of bridges 3 of insulating material are mounted, and between which, longitudinal wires 4 of any suitable 60 high resistance metal are strung over the bridges 3. The transverse wires 5, which are of copper or any other suitable heat conducting material, are so related to the longitudinal wires 4 as to form an open mesh net 65 work, and may be mounted in any suitable way which will bring them into good thermal 70 relation to the high resistance wires, so that the transverse wires form electrical connections between the longitudinal wires and 75 also rapidly conduct the heat away from them. The transverse wires may be loosely interlaced with the longitudinal wires, if desired, but in the preferred construction the longitudinal wires are all mounted in the 80 same plane, while the transverse wires 5 are strung in firm engagement with the longitudinal wires and over insulating bridges 6 mounted on a movable metallic support 7, 85 which is provided with a handle 8 and is pivotedly secured to the base 1 by means of a stud or pivot 9. All of the wires 5 may be simultaneously moved with reference to the longitudinal wires by shifting the adjustable support 7. When the adjustable support is 90 in the position shown in Fig. 1, the resistance of the device is the maximum; as the adjustable support is turned about the pivot 9 the angle between the transverse wires 5 and the resistance wires 4 becomes more and 95 more acute, and at the same time the ohmic resistance between terminals 2 decreases, until finally when the wires 5 are substantially parallel to the resistance wires 4 the ohmic resistance of the device is a minimum. By 100 means of this construction the ohmic resistance may be increased or decreased in a uniform manner instead of by steps, as in many forms of adjustable resistance heretofore used.

My invention may be embodied in many other forms than that shown and described, and I do not limit it to the precise arrange-

ment disclosed, but intend to cover by the appended claims all forms and modifications within the spirit and scope of my invention.

What I claim as new and desire to secure 5 by Letters Patent of the United States, is,—

1. In an adjustable resistance, the combination with longitudinal high resistance wires, of transverse heat conducting wires adjustably mounted in good thermal relation 10 to said longitudinal wires to form a network and to be adjustable to vary the angle between said longitudinal wires and said transverse wires.

2. An adjustable resistance comprising 15 wires arranged to form a network in which the wires may at will be adjusted with reference to one another.

3. An adjustable resistance comprising 20 longitudinal wires, supports for said longitudinal wires, and transverse wires loosely arranged with reference to said longitudinal wires to form a network in which the angle between each transverse wire and the longitudinal wires may be varied at will.

25 4. An adjustable resistance comprising wires of different metals arranged to slide over each other and to form a network in which the wires are relatively adjustable.

30 5. In an adjustable resistance, the combination with longitudinal wires, of transverse wires mounted in sliding engagement with said longitudinal wires to form a net-

work and to be adjustable with reference to said longitudinal wires whereby the angle between said transverse and said longitudinal wires may be varied at will. 35

6. An adjustable resistance comprising wires of manganin and transverse wires of copper mounted to engage said manganin strips to form a network and to slide over 40 said strips to vary the angle between said manganin strips and said copper wires.

7. In an adjustable resistance, the combination with resistance wires, of transverse wires movably mounted in engagement with 45 said resistance wires, and means for simultaneously moving all said transverse wires relatively to said resistance wires.

8. An adjustable resistance comprising 50 longitudinal wires of high resistance metal, a support for holding said wires in position to permit free access of air, a second support adjustably mounted with relation to said resistance wires, and coöperating wires mounted on said second support to engage said high resistance wires, whereby the angle between said coöperating wires and said high resistance wires may be varied. 55

In witness whereof, I have hereunto set my hand this 6th day of January, 1910.

ROBERT MILLER, JR.
